UNITED STATES PATENT OFFICE

HARRY L. KUCHINS, OF NORMANDY, MISSOURI

DESIGN FOR A KITCHEN CABINET

Application filed April 9, 1932. Serial No. 43,447. Term of patent 3½ years.

To all whom it may concern:

Be it known that I, HARRY L. KUCHINS, a citizen of the United States, residing in Normandy, in the county of St. Louis and State of Missouri, have invented a new, original, and ornamental Design for Kitchen Cabinets, of which the following is a specification, reference being had to the accompanying drawing, forming part thereof.

The figure is a perspective view of a kitchen cabinet, showing my new design and having the representations of tiling arranged on the doors thereof.

I claim:

The ornamental design for a kitchen cabinet, as shown and described.

HARRY L. KUCHINS.
